UNITED STATES PATENT OFFICE.

OTIS CUTTING, OF SEATTLE, WASHINGTON.

DESIGN FOR A DECARBONIZER.

53,892.

Specification for Design.

Patented Oct. 7, 1919.

Application filed April 12, 1919. Serial No. 290,092. Term of patent 3½ years.

To all whom it may concern:

Be it known that I, OTIS CUTTING, a citizen of the United States, whose post-office address is 1013 L. C. Smith Building, in the city of Seattle, county of King, and State of Washington, have invented a new, original, and ornamental Design for a Decarbonizer, of which the following is a specification, reference being had to the accompanying drawing, forming a part thereof.

The figure is an elevational view of a decarbonizer adapted to be placed upon motor vehicles, showing my new design.

I claim:

The ornamental design for a decarbonizer, as shown.

OTIS CUTTING.
